TIRE

James Girdner, Lodi, Calif., assignor to Super Mold Corporation of California, Lodi, Calif., a corporation of California

Application June 4, 1957, Serial No. 46,475

Term of patent 14 years

(Cl. D90—20)

FIG-1

FIG-2

FIG-3

Fig. 1 is a top plan view of a tire showing my new design, it being understood that the design shown in full lines is repeated throughout the circumference of the tire shown in broken lines.

Fig. 2 is a fragmentary cross sectional view thereof taken on line 2—2 of Fig. 1.

Fig. 3 is a fragmentary side elevational view of Fig. 1. The dominant features of my design reside in the full line portions of the drawing.

I claim:

The ornamental design for a tire, as shown and described.
